UNITED STATES PATENT OFFICE.

JOHN H. RING, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A BACK FOR MIRRORS, BRUSHES, OR SIMILAR ARTICLES.

54,454.

Specification for Design.

Patented Feb. 10, 1920.

Application filed May 23, 1919. Serial No. 299,346. Term of patent 14 years.

To all whom it may concern:

Be it known that I, JOHN H. RING, a citizen of the United States, residing at Providence, in the county of Providence and State of Rhode Island, have invented a new, original, and ornamental Design for Backs for Mirrors, Brushes, or Similar Articles, of which the following is a specification, reference being had to the accompanying drawing, forming part thereof.

The figure in the drawing is an obverse

view of a back for mirrors, brushes, or similar articles, the section indicated, showing my design.

I claim:

The ornamental design for a back for mirrors, brushes, or similar articles, as shown.

JOHN H. RING.

Witnesses:

AXEL H. STAFA,
W. F. KINGMAN.
